CLAIM

The ornamental design for a marking device, as shown and described.

DESCRIPTION

FIG. 1 is a top isometric view of an embodiment of a marking device.
FIG. 2 is a bottom isometric view of the marking device of FIG. 1.

FIG. 3 is a top plan view of the marking device of FIG. 1.
FIG. 4 is a bottom plan view of the marking device of FIG. 1.
FIG. 5 is a front elevational view of the marking device of FIG. 1.
FIG. 6 is a rear elevational view of the marking device of FIG. 1; and,

FIG. 7 is a right side elevational view of the marking device of FIG. 1. The left side elevational view is substantially a mirror image of the right side elevational view.

PATENT NO. : D719,856 S
APPLICATION NO. : 29/448798
DATED : December 23, 2014
INVENTOR(S) : Bruce B. Dressel et al.

Page 1 of 1

It is certified that error appears in the above-identified patent and that said Letters Patent is hereby corrected as shown below:

On the title page under Description, Figure 7, line 11:

“FIG. 7 is a right side elevational view of the marking device of FIG. 1. The left side elevational view is substantially a mirror image of the right side elevational view.” should read, --FIG. 7 is a right side elevational view of the marking device of FIG. 1.--.
